UNITED STATES PATENT OFFICE.

OSWALD C. LEGER, OF LOS ANGELES, CALIFORNIA.

BILLIARD-CUE CONSTRUCTION AND METHOD OF ATTACHING THE CUE-TIP.

1,340,395.

Specification of Letters Patent.

Patented May 18, 1920.

Application filed October 15, 1919. Serial No. 230,731.

To all whom it may concern:

Be it known that I, OSWALD C. LEGER, a citizen of Great Britain, having declared my intention of becoming a citizen of the 5 United States, residing at Los Angeles, in the county of Los Angeles and State of California, have invented a new and useful Billiard-Cue Construction and Methods of Attaching the Cue-Tip, of which the following 10 is a specification.

This invention relates to billiard cues and also to the method of attaching the tips thereof, and an object of the invention is to provide a tip which is not liable to become accidentally detached and one which can be 15 readily replaced by a new one in event of accidental detachment or an undesirable amount of wear occurring.

Another object is to provide a construction which will permit of a screw-threaded attachment of the tip, the construction being such that a frictional lock is provided between the screw-threaded members so as to 20 guard against relative unscrewing of said 25 members.

Another object is to avoid the use of a clamp in securing the tip to the cue.

Other objects and advantages will appear hereinafter.

30 The accompanying drawings illustrate the invention:

Figure 1 is a longitudinal view of a billiard cue embodying the invention.

Fig. 2 is an enlarged elevation, partly in 35 section, of the ball-striking end of the billiard cue shown in Fig. 1.

Fig. 3 is an enlarged sectional elevation on line indicated by x^3-x^3 , Fig. 2.

40 Figs. 4 and 5 are plan views partly in section on lines indicated by x^4-x^4 and x^5-x^5 , Fig. 3.

Fig. 6 is a plan view of the tip holding member.

45 Fig. 7 is an inverted plan view of the cue tip.

Fig. 8 is an edge view of the shield.

Fig. 9 is a perspective view of the stud-engaging member.

50 Fig. 10 is a plan section on line indicated by $x^{10}-x^{10}$, Fig. 3.

Fig. 11 is a sectional elevation on line indicated by $x^{11}-x^{11}$, Fig. 6.

Fig. 12 is an enlarged vertical section of the stud-engaging member.

55 The tip proper is indicated at 1 and is more or less rounded on its outer end and is

provided on its inner end with a dove-tail projection in the form of an annulus 2. The projection 2 seats in an annular recess 3 in the outer end of a tip holding member 4. The side walls of the recess 3 are aslant so as to reduce the recess inwardly. Thus the recess is of dove-tail shape.

The tip 1 is made of suitable yielding or buffer material such as leather or the like and, 65 in manufacture, the annulus may be made with its side faces parallel with the axis of the tip and, before applying to the tip holding member 4, the tip is moistened and then pressed or hammered forcibly into place 70 so as to cause the annulus 2 to spread laterally in the recess and engage the walls of the recess 3 and substantially fill and fit said recess. The annulus 2 because of the moisture swells and thus grips the recess 3 very 75 tightly and when the tip dries the annulus does not shrink to its original shape but because of the dove-tail shape of the annulus and recess continues to be firmly held.

The tip holding member 4 is preferably 80 made of fiber or other suitable non-metallic material and is provided axially thereof with a tubular recess 5 to hold a stud engaging member 6. The periphery of the stud engaging member 6 is corrugated, the 85 corrugations 7 being slightly aslant to the longitudinal axis of the member 6 so that when said member is driven into the member 4 it will rotate slightly and therefore cannot be withdrawn without giving it a reverse 90 rotation and in manufacture the bore 5 will be made of a diameter corresponding to the diameter of the member 6 at the root or base of the corrugations 7 so that when the member 6 is driven into the bore 5 the corrugations will cut into the inner surface of the wall of the bore 5 and thus securely hold the members 4, 6 against relative displacement. Thus to all intents and purposes the member 6 becomes, after assembly, 95 a functional part of the member 4.

The member 6 is provided axially thereof with a screw-threaded bore 8 which communicates at its outer end with an enlarged bore or recess 9. In threading the bore 8 105 the tap is threaded into the bore produced by the drill and stopped when its point projects slightly into the bore 9, thus causing the screw-threads 10 near the outer end of the bore 8 to be of less diameter than the 110 remainder of the screw-threads, since the end threads of the tap, as is well understood,

are of less diameter than the remainder of the threads of the tap.

The member 6 is screw-threaded onto a screw-threaded stud 11 which in turn is seated in a screw-threaded socket 12 formed in the outer end of a pin 13. When the member 6 is screwed home on the stud 11 the smaller diameter threads 10 are forced into close engagement with the threads 10 of the stud, the friction being sufficient to hold the member 6 against unscrewing unless considerable force is applied for that purpose when it is desired to remove the member 4.

15 To prevent any liability of the stud 11 accidentally engaging the outer end wall of the recess 5 and forcing said wall outwardly and thus disturb the tip, a shield 14 is interposed between the outer end of the stud 20 11 and said end wall and this shield constitutes a further frictional means between the member 4 and the stud to tend to prevent unscrewing of the member 4, since when the parts are assembled, the shield 14 25 seats against the outer end wall of the recess 5 and the outer end of the stud 11 engages the shield. It is understood that in practice the manufacturer will make and assemble extra tips 1, tip holding members 4, stud 30 engaging members 6 and shields 14 so as to form spare units adapted to replace like parts of cues already in use constructed in accordance with this invention, in event of the tip 1 coming loose from the member 4 or 35 becoming objectionably worn.

The advantage if this construction will be clear when it is considered that at present cue tips are glued directly to the ends of the cue bodies or stems and when a tip comes 40 off of such a cue it is necessary to re-glue it and temporarily secure it by a clamp to the stem of the cue for several hours or until the glue dries. In the clamping operation the clamp injures the stem of the cue adjacent the tip and it is this tip portion of 45 the cue that rests on or within the hand of the player. The depressions and roughness caused by the clamp are very objectionable to the cue user and in fact are at times serious enough to destroy accuracy in playing. 50 My construction obviates this marring of the cue when the replacement of the tip is necessary.

The pin 13, in the manufacture of the cue, 55 is driven through a bore 15 of a member 16, said bore being provided with a shoulder 17 adapted to be engaged by a shoulder 18 on the pin 13. The bore 15 communicates with a larger bore 19 of the bore 16 and the 60 larger bore 19 receives the reduced end 20 of the body or stem 21 of the cue. The pin 13 besides extending through the bore 15 is driven into an axial bore 22 in the outer 65 end portion of the cue stem 21, and the pin 13 is provided at its periphery with longi-

tudinal corrugations 23 which extend slightly aslant to the longitudinal axis of the pin so that when the pin is driven into the bore 22 it will rotate slightly and thus require reverse rotation to extract the pin. 70 In manufacture the bore 22 is made substantially of the same diameter as the corrugated portion of the pin at the bases or roots of the corrugations so that when the pin is driven into place the corrugations 23 75 cut into the inner surface of the wall of the bore 22. The stem 21 is constructed of any suitable wood and the member 16 may be of ivory or any other desired material that is suitable for the purpose. The stud 11, 80 stud-engaging member 5, shield 14 and pin 13 are of any suitable metal such, for example, as brass.

In practice the cue will be constructed as above described and if, in use, the tip 1 85 comes loose from the member 4 the member 4 together with the parts permanently attached thereto will be rotated to unscrew the member 6 from the stud 11 and a similar member 4 with a tip 1 attached thereto and 90 with parts corresponding to the members 6 and 14 assembled therewith will be applied to the stud 11 by rotating the member 4. Thus it is clear that the cues constructed in accordance with my invention need not be 95 out of service, because of the tip coming off, for any greater length of time than is necessary to unscrew the member 6 from the stud and replace the parts thus removed with a new corresponding assembly of parts forming a 100 spare unit. Nor will the cue be injured so as to tend to destroy the aim of the user of the cue.

The invention is not limited in its broader phases to the exact details of construction 105 described above and shown in the drawings, but embraces such changes and modifications as lie within the spirit and scope of the appended claims.

I claim:

1. In a cue, a tip holding member provided with an annular dove-tail recess, and a tip having a dove-tail annulus in the recess and formed of a yielding material which expands when moistened.

2. In a cue, a tip holding member provided with a recess, a stud-engaging member in the recess having a screw-threaded bore and having a larger bore communicating with the screw-threaded bore, the screw- 120 threads nearer the outer end of the bore being initially of smaller diameter than the other screw-threads, a stem, a stud connected with the stem and screw-threaded to engage the screw-threaded bore and projecting into 125 the larger bore of the stud-engaging member, and a yielding tip fastened to the tip-holding member.

3. In a cue, a tip holding member provided with a recess, a stud-engaging member 130

in the recess having a screw-threaded bore, and having a larger bore communicating with the screw-threaded bore, the screw-threads nearer the outer end of the bore being initially of smaller diameter than the other screw-threads, a stem, a pin connected with the stem and provided with a screw-threaded socket, a stud screw-threaded into the socket and into the screw-threaded bore 10 and projecting into the larger bore of the stud-engaging member, and a yielding tip fastened to the tip-holding member.

4. In a cue, a tip holding member pro-

vided with a recess, a stud-engaging member in the recess having longitudinal corrugations slightly aslant to the longitudinal axis of said member, a stem, and a stud screw-threaded into the stud-engaging member 15 and connected with the stem.

Signed at Los Angeles, California, this 20
9th day of October, 1919.

OSWALD C. LEGER.
